US0D1034701S

(12) **United States Design Patent** (10) Patent No.: **US D1,034,701 S**
(45) Date of Patent: ** Jul. 9, 2024

(54) **MANIFOLD**

(71) Applicant: **Holley Performance Products, Inc.**,
Bowling Green, KY (US)

(72) Inventors: **Corey D. Spainhoward**, Bowling
Green, KY (US); **Jamie Wagner**,
Scottsville, KY (US); **Timothy A.**
Grillot, Alvaton, KY (US); **Adam**
Layman, Alvaton, KY (US)

(73) Assignee: **Holley Performance Products, Inc.**,
Bowling Green, KY (US)

(**) Term: **15 Years**

(21) Appl. No.: **29/878,154**

(22) Filed: **Jun. 16, 2023**

Related U.S. Application Data

(62) Division of application No. 29/713,833, filed on Nov.
19, 2019, now Pat. No. Des. 997,990.

(57) **CLAIM**

The ornamental design for a manifold, as shown and
described.

DESCRIPTION

FIG. 1 is an upper perspective view of a manifold showing
our new design;

FIG. 2 is a front view of the design of FIG. 1;

FIG. 3 is a rear view of the design of FIG. 1;

FIG. 4 is a first side view of the design of FIG. 1;

FIG. 5 is a second side view of the design of FIG. 1;

FIG. 6 is a top view of the design of FIG. 1;

FIG. 7 is a bottom view of the design of FIG. 1; and,

FIG. 8 is a lower perspective view of the design of FIG. 1.
The broken lines shown in the drawings are illustrating
unclaimed portions of the manifold and form no part of the
claimed design.

1 Claim, 8 Drawing Sheets
